UNITED STATES PATENT OFFICE.

JAMES H. RAND, OF NEWTONVILLE, MASSACHUSETTS.

CARD-LEDGER.

No. 801,608.

Specification of Letters Patent.

Patented Oct. 10, 1905.

Application filed July 10, 1905. Serial No. 268,960.

To all whom it may concern:

Be it known that I, JAMES H. RAND, a citizen of the United States, residing at Newtonville, in the county of Middlesex and State of Massachusetts, have invented a new and useful Improvement in Card-Ledgers, of which the following is a specification.

This invention relates to a card record or ledger designed for use in banks and mercantile establishments in place of ordinary ledgers or record-books.

The object of my invention is to provide an improved device of this character which permits entries to be conveniently made on the various account or record cards and enables any of the accounts to be quickly referred to.

In the accompanying drawings, consisting of two sheets, Figure 1 is a top plan view of the device, showing detachable account-envelops on the flaps of the voucher files or holders. Fig. 2 is a longitudinal section thereof, showing holders adapted to receive entries directly upon their flaps. Fig. 3 is an end view of one of the holders shown in Fig. 1. Fig. 4 is a perspective view of another modification of the holder. Fig. 5 is a perspective view of a modified form of the detachable voucher-envelops. Fig. 6 is a transverse section of the last-mentioned folder in line 6 6, Fig. 5.

Similar letters of reference indicate corresponding parts throughout the several views.

A indicates a rectangular case or drawer adapted to receive a series of upright voucher holders, files, or pockets B. Each of these preferably consists of a two-leaf folder, the rear wall or leaf of which is provided at its upper edge with a flap C, flexibly connected therewith, so that the flap can be swung or folded in either direction. The flaps of the several holders normally overlap one another, as shown in Figs. 1 and 2, and each flap is adapted to receive account entries or other records either directly by suitably ruling its face or by means of detachable account or record cards or removable envelops or folders appropriately ruled on their faces and adapted to contain bank-vouchers or other papers relating to the corresponding accounts.

In the embodiment of the invention shown in Figs. 1 and 3 each flap C carries an open-ended voucher-envelop D, which is removably attached thereto by inserting the corners of the envelop in oblique slits d, cut in the adjacent portions of the flap. These envelops bear the names of the respective accounts and

are ruled into suitable columns having appropriate headings, as shown.

Each flap C is provided at its free edge with an index-tab e, which projects rearwardly from the flap and bears the name, number, or other index designation of the corresponding account. The tabs of adjoining flaps are offset or arranged out of line with each other lengthwise of the device, so that they are all visible and can be readily seized for referring to a given ledger-card or making an entry thereon. As the flaps are free to swing back and forth, this can be readily done without removing the holders B from the box or drawer A.

In the construction shown in Fig. 2 the entries are made directly upon the flaps C, which in this case are ruled according to the requirements of the bank or other business for which the device is intended.

In the modification shown in Fig. 4 the flaps are provided with detachable account cards or slips D', having end tongues f, which engage in slits f', formed in the flaps.

If desired, the voucher-envelops shown in Figs. 1 and 3 may be in the form of a two-leaf folder D², as shown in Figs. 5 and 6. The upper leaf of this folder may have end tongues like the record-card illustrated in Fig. 4, and its lower leaf may be provided with a transparent panel g, arranged to expose the signature on the front check of the package of vouchers placed in the folder.

In the use of the devices shown in Figs. 1, 3, 5, and 6 the bank-vouchers are returned to the depositors in the folders or envelops when their accounts are balanced. In using the ledger shown in Fig. 4 when a record or account card is filled up it is removed to a suitable transfer-file and replaced by a new card.

While the holders B are designed to contain vouchers or other papers, they may in some cases be used simply as retainers for holding the flaps C in place.

My improved card-ledger not only facilitates the making of entries, but effects an important saving of time when used as a voucher-file.

I claim as my invention—

1. A card record or ledger, comprising a drawer or receptacle, holders arranged therein and each having a swinging record-flap provided at its free edge with an index-tab, the several flaps overlapping one another, substantially as set forth.

2. A card record or ledger, comprising a

2
drawer or receptacle, holders arranged there-
in and provided at their upper edges with
swinging flaps which overlap one another, and
detachable record-surfaces carried by said
5 flaps, substantially as set forth.

3. A card record or ledger, comprising a
drawer or receptacle, holders arranged there-
in and provided at their upper edges with
swinging flaps which overlap one another,
10 each flap being provided at its free edge with
an index-tab, and detachable record-surfaces
carried by said flaps, substantially as set forth.

4. A card record or ledger, comprising a
drawer or receptacle, holders arranged there-
in and provided at their upper edges with
swinging flaps which overlap one another, and
detachable voucher-envelopes carried by said
15 flaps and suitably ruled on their faces to re-
ceive entries, substantially as set forth.

20 5. In a card record or ledger, a holder hav-
ing a swinging record-flap provided at its edge
with an index-tab, substantially as set forth.

6. In a card record or ledger, a holder pro-
vided at its upper edge with a swinging flap
and a detachable record-surface carried by said 25
flap, substantially as set forth.

7. In a card record or ledger, a holder pro-
vided at its upper edge with a swinging flap
and a record-envelop detachably secured to
said flap and suitably ruled on its face to re- 30
ceive entries, substantially as set forth.

8. In a card record or ledger, a voucher-
holder, comprising an open-ended folder pro-
vided at the upper edge of one of its leaves
with a swinging flap having slits and a pro- 35
jecting index-tab, and a detachable record-
surface engaging in said slits, substantially as
set forth.

Witness my hand this 26th day of June, 1905.

JAMES H. RAND.
